United States Patent Office

Des. 181,891
Patented Jan. 7, 1958

181,891

LETTER SCALE

Horace L. Walborn, Jackson, Mich.

Application August 13, 1957, Serial No. 47,352

Term of patent 14 years

(Cl. D52—10)

Fig. 1

I claim:

The ornamental design for a letter scale, as shown.
